UNITED STATES PATENT OFFICE.

ELMER M. COBB, OF SOUTH PORTLAND, MAINE, ASSIGNOR TO SOUTHWORTH MACHINE COMPANY, OF PORTLAND, MAINE, A CORPORATION OF MAINE.

PRINTER'S APPLIANCE.

1,187,417.

Specification of Letters Patent. Patented June 13, 1916.

Application filed September 9, 1915. Serial No. 49,818.

To all whom it may concern:

Be it known that I, ELMER M. COBB, a citizen of the United States, and resident of South Portland, county of Cumberland, 5 State of Maine, have invented an Improvement in Printers' Appliances, of which the following description, in connection with the accompanying drawings, is a specification, like characters on the drawings representing like parts in each of the several 10 views.

This invention relates to a printer's appliance particularly designed and adapted for use in job printing offices for engaging 15 and releasing the clamp which holds the pad or backing to the platen.

More especially the present appliance is formed and adapted for use with a job printing press of the well known Chandler & 20 Price type or the like to engage the tympan bail at the top and bottom of the inclined platen in this type of press.

The invention will be better understood from the following description taken in connection with the accompanying drawings 25 and will be thereafter pointed out in the appended claims.

Referred to the drawings: Figure 1 is a front elevation somewhat in perspective 30 showing my improved appliance; Fig. 2 is an edge view thereof; and Fig. 3 is an elevation showing the use of the device in operating the tympan bail of a platen.

The present appliance consists in a head 35 10 preferably oblong and generally rectangular with flat side faces 11, 12, and somewhat convexed ends 13, 14, though this particular form of head is not essential to the carrying out of the principles of the invention. From this head a handle 15 projects 40 in a direction generally parallel to the lateral faces of the head, particularly the front face 12 which is the operative portion of the device for engaging the part to be operated.

45 The outer end of the handle 15 may be formed with a wrench head 16 and the convexed end 13, 14, of the head may be used as hammer heads adapting the device to be used for hammering, though these are 50 merely incidental attributes, and not essential to the practice of the invention. In accordance with my invention I form in the front flat face 12 of the head 10, diagonal recesses or grooves 17, 18 extending as shown 55 from diagonally opposite corners of the

head and intersecting centrally. These grooves are formed with rectangular shoulders at their sides and are each of a size to receive and fit the tympan bail to move the same by engagement thereof with the shoulders or ledges at the sides of said grooves. It will be understood that the platen to the upper and lower sides of which the tympan bail is attached, is inclined with its faces extending diagonally downward away from 60 the operator. Thus in using the appliance for engaging the tympan bail, as to release the same, when the bail at the top is to be engaged, the device is applied to the same with the groove 18 engaging the bail, and 65 with this engagement the handle 15 will project upward substantially upright and convenient to the hand of the operator. When the tympan bail at the bottom or lower inclined side of the platen is to be engaged, 70 the device is applied thereto with the groove 17 fitted to the same, which will result in the handle 15 projecting upward and outward in convenient position for the operator.

75 It will be further understood that while the handle 15 thus projects up in a convenient direction for the hand of the operator as he stands back of the platen, with the grooves 17, 18 thus selectively engaged as described with the tympan bail at top and 80 bottom of the platen, should it be attempted to engage the same groove with the tympan bail in both positions, it would inevitably cause projection of the handle in an awkward or impossible direction in one or both 85 cases. It will of course be understood that the direction of the two diagonal grooves 17, 18, will be so disposed that the handle will project to the most convenient angle for the hand of the operator in each case. It is 90 preferable to form both these diagonal grooves 17, 18 in the same face of the head of the appliance, since thereby metal stock is economized and the device can be made at the same time strong, light and convenient 95 to operate. In Fig. 3 a printing press platen is indicated at P, this platen being usually set at an incline as in the Chandler and Price type of press with the side at the right of said figure inclined upward. The 100 tympan bail B at the lower edge of the platen is here engaged with the groove 17 of the device while the bail B' at the upper edge of the platen will be engaged by the groove 18, the handle 15 in each case being 105 110

presented at a convenient angle for operation.

I do not desire to be limited to the precise design and detailed construction herein exhibited and therefore desire the present embodiment to be considered as illustrative, and not restrictive, reference being had to the appended claims rather than to the foregoing description to indicate the scope of the invention.

Having described my invention, what I claim as new and desire to secure by Letters Patent is:

1. A printer's appliance, comprising a head having two grooves in a face thereof extending at an angle to each other, and a handle projecting from said head and extending in general parallelism with the plane of said grooves, one of said grooves being adapted to engage a tympan bail at the bottom of the platen and the other at the top of the platen with the handle in each case projecting to a point convenient for the operator.

2. A printer's appliance, comprising a head having two grooves formed in a face

thereof at an angle to each other and intersecting, and a handle projecting from said head in general parallelism with the plane of said grooves, said grooves being formed with straight shoulders at their sides and of a size to fit a tympan bail, one of said grooves being adapted to engage a tympan bail at the bottom of a platen and the other groove to engage a tympan bail at the top of a platen with said handle in each case projecting to a point convenient for the operator.

3. A printer's appliance, comprising a flat, oblong and generally rectangular head with intersecting grooves extending from diagonally opposite corners, formed in one face thereof, one of said grooves being adapted to fit a tympan bail at the bottom of a platen and the other groove a tympan bail at the top of a platen with said handle in each case projected to a point convenient to the operator.

In testimony whereof, I have signed my name to this specification.

ELMER M. COBB.
